CLAIM

The ornamental design for an induction appliance, as shown and described.

DESCRIPTION

FIG. 1 is a perspective view of the induction appliance;
FIG. 2 is a front elevation view thereof;
FIG. 3 is a rear elevation view thereof;
FIG. 4 a right side elevation view thereof;
FIG. 5 is a left side elevation view thereof;
FIG. 6 is a top plan view thereof; and,
FIG. 7 is a bottom plan view thereof.
The broken lines in the drawings represent unclaimed subject matter and form no part of the claim.
